Specification of Letters Patent.

Patented Mar. 7, 1916.

Application filed March 11, 1915. Serial No. 13,736.

To all whom it may concern:

Be it known that we, HENRY A. CARPENTER and ARTHUR W. WARNER, citizens of the United States, residing at Sewickley, in the county of Allegheny and State of Pennsylvania, have invented certain new and useful Improvements in Charging-Machines, of which the following is a specification.

Our present invention relates to improvements in charging machines for gas generating apparatus, and more particularly to the charger operating mechanism.

In operating chargers, and especially of that type in which the carrier for the coal is moved into and out of a retort, an example of which is disclosed in the patent to Carpenter and Hibbard, Number 1,144,165, dated June 22, 1915, wherein the charger is given its longitudinal movements by means of a threaded shaft adapted to be driven by a motor, operating difficulties may occur due to the effects of the coal carbonization in the retorts as well as other causes. For instance, the charger shown in said patent is adapted for use in connection with what are known as through retorts, the charger operating to discharge the incandescent mass during the movement to charging position.

In operation, it is possible during the movement of the charger in the retort, that it may be subjected to too heavy resisting actions due to the accumulation of the incandescent mass in advance of the charger or through the failure to properly open the discharge end of the retort. As the motor must necessarily be of a capacity sufficient to provide the proper operation under general conditions, it will be understood that should such resisting action be present, there is great liability of damage to the equipment, especially to the coal carrier, which in the particular instance noted, is in the form of thin metal scoops of extended length and supported at their inner ends. Another tendency to provide this resisting action of pressure is the presence of the carbon deposits within the retort. Where these deposits are sufficiently large to cause the scoops to bind during their movement in the retort, resisting pressure will be provided, especially if the scoops, in moving in the retort should tend to ride upwardly within the retort, the extended length of the scoops being such as to cause a slight riding effect at

the entrance to be magnified when the scoops have been inserted a considerable distance. To prevent material damage to the motor under these conditions, a friction clutch has been mounted on the threaded shaft, between the shaft and the motor, a construction of this type being disclosed in the said patent, but the great tendency to wear, and other difficulties relative to the particular type of clutch shown are such as to tend to cause a rapid deterioration in the structure when so equipped. While the provision of a suitable clutch mechanism will tend to restrict damage to the motor, another feature in connection with the difficulties arising by reason of this excess resisting pressure, is the liability of destruction of the charger unless the difficulty is quickly overcome and the charger withdrawn. It is obvious that the intense heat of the retort (ranging as high as 2,000 degrees F.) will quickly destroy the metal scoops if they are allowed to remain within the retorts for any extended period. In the normal operation of a charging machine of the general type shown in said patent, the length of time the scoops remain within the retort, under proper operation, is less than 20 seconds, a time insufficient to permit material damage to the scoops. However, should a stoppage to the movement of the scoops occur, the time required to relieve the condition, may greatly exceed that period, unless provision is made to relieve it rapidly. If the stoppage is due simply to an accumulation of material in advance of the charger, the latter being otherwise free, a simple reversal of the direction of movement of the motor will cause the carrier to be rapidly withdrawn. Where, however, the scoops stick or have become bound within the retort, a simple reversal of the motor may be insufficient to provide such withdrawal action. In prior devices, as for instance the structure of the said patent, it has been the practice, in such case, to employ some means at the end of the threaded shaft for manually manipulating the shaft in an attempt to overcome the condition noted, but this necessitated action on the part of the operator in securing the necessary tools, etc., to provide the operation, requiring an expenditure of time far exceeding the period of time during which the scoops should remain in the retorts with safety. In the present

invention, these difficulties are overcome by the use of a friction clutch of a type which will provide serviceability and which can be readily adjusted to control the amount of friction, thus providing efficient means for preventing damage to the motor under such stoppage conditions. At the same time, we provide an emergency mechanism normally free from engagement with the shaft-driving mechanism, but positioned to enable the operator to quickly provide connection between such mechanism and the threaded shaft, a construction that will permit the operator to manually exert considerable power on the shaft in the proper direction to aid in the release of the stoppage conditions. The connections of the mechanism are such as to multiply the power with resultant loss of speed; however, as the withdrawal action under this manual operation is of such short duration (since the stoppage is generally of such a character that a very small movement is sufficient to overcome the stoppage condition and permit the motor to provide the normal withdrawal operation), this loss in speed is immaterial.

We prefer to arrange the mechanism in such manner that the movement of parts in bringing the emergency mechanism into operation will automatically break the motor circuit, the mechanism providing a make and break device in the circuit for the motor.

In the accompanying drawings, in which similar reference characters indicate similar parts in each of the views, Figure 1 is a diagrammatic view showing a charging and a discharging machine with our invention applied thereto, the view also showing a portion of a gas bench having a retort therein. Fig. 2 is a vertical sectional view taken through the emergency mechanism and showing a portion of the threaded shaft. Fig. 3 is a vertical sectional view taken on line 3—3 of Fig. 2. Fig. 4 is a detail sectional view taken on line 4—4 of Fig. 3. Figs. 5 and 6 are detail views of preferred forms of disk structures employed in connection with the clutch. Fig. 7 is a detail view, partly in section, showing the means employed for operating the emergency mechanism to carry it into and out of engagement with the threaded shaft.

The general idea of the present invention is disclosed in Fig. 1, in which 10 designates the frame of a charging machine, and 11 the charger, the latter being operatively connected to a threaded shaft 12 by suitable means such as a nut 13. The shaft 12 is shown as driven by a motor 14 through drive connections indicated generally at 15, the movements of the motor causing the nut to be threaded lengthwise of the shaft and thus cause movements of the charger in the direction of its length. In Fig. 1,

the charger is shown as entered within the retort 16, the showing indicating that the charger is approaching the position at which the retort is charged. The normal position of the charger is below a chute structure indicated conventionally at 17 by means of which a new charge is supplied to the charger at the proper time. As will be readily understood, the charger may be subjected to the difficulties heretofore referred to in moving into the retort, and as the scoops are of considerable length (a generally accepted length being 16 feet), it will be readily understood that any unusual delay in the withdrawal of the scoops will subject them to the action of the high temperatures with liability of destruction. The means we employ for tending to prevent damage to the equipment will now be described in detail.

Referring first to Fig. 3, 18 designates a casing mounted on the frame work of the charging machine, and into which the shaft 12 extends, said shaft being shown as provided with a shoulder 12^a, and a spindle 12^b, the shoulder and the spindle being located within the casing. 19 indicates the shaft of motor 14, said shaft also extending within the casing 18, and is shown as provided with a gear or pinion 20. Between the gear 20 and the shaft 12 we mount a friction clutch, preferably of the type disclosed herein. This clutch comprises a gear member 21 having an inwardly extending web 21^a, the inner portion of the web terminating in a collar 21^b, said collar being mounted on a bushing 22 located between the casting 23 and said collar 21^b. The casting 23 is preferably of the cross sectional shape shown in said Fig. 3, being provided with an inwardly projecting annular flange 23^a spaced from the outer periphery of the casting or member 23. The casting is splined or otherwise secured to the spindle 12^b to rotate therewith, but free to move longitudinally of the spindle as may be necessary. 24 designates a member, also splined or otherwise secured to the spindle 12^b, said member being adapted to abut against the shoulder 12^a, but free to move longitudinally of the shaft in the opposite direction. Said member also carries an inwardly extending annular flange 24^a which co-operates with the flange 23^a to form a space for the collar 21^b and the bushing 22.

As shown more particularly in Fig. 4, the gear 21 is provided with a plurality of keys or similar devices 25; similarly, the members 23 and 24 are also provided with keys or similar devices 26, these extending in directions parallel to the axes of these members, and projecting into the spaces formed between the flanges 23^a and 24^a and the gear 21 on opposite sides of the web 21^a. Mounted within these spaces are the members

shown in detail in Figs. 5 and 6, these members being flat and arranged in alteration, the member 27 being formed to engage the keys 25 so as to rotate with the gear 21, while the member 28 is formed to engage the keys 26, thus placing it in fixed connection with either member 23 or member 24, depending upon the space within which it is positioned. As will be understood, a plurality of these members are employed on each side of the web, and being interleaved, it will be understood that if sufficient force be applied, a frictional engagement will be provided between the two sets of members within the spaces. To provide the necessary friction, we preferably employ a suitable compression device or equivalent structure, the device shown being in the form of a compression spring 29 mounted between the face of member 23 and a washer 30, the amount of compression placed upon the spring being adjustable by the use of nut 31. By this particular arrangement, it will be seen that the spring 29 will tend to move the parts of the clutch toward the left in Fig. 3, but since the movement of member 24 in this direction is limited by the shoulder 12^a, it will be readily understood that this pressure of the spring will cause the members 27 and 28 to be frictionally engaged by reason of the direct pressure placed thereon by the opposing walls of the members 23 and 24 and the web 21^a, the gear 21 being movable axially such distance as is required by this action. As a result, a drive from the motor shaft 19 to the threaded shaft 12 is provided through the gear or pinion 20, gear 21, members 27 and 28, and members 23 and 24 to the spindle. This drive arrangement will continue as long as the resistance of the shaft 12 is less than the friction produced by the compression pressure of the spring 29. When this resistance of the shaft 12 exceeds such pressure, it will be readily understood that the interleaved members 27 and 28 will move relatively to each other and thus change the speed relation between the shafts 12 and 19 even to a point where the shaft 12 actually stops rotating. As will be understood, a variation in compressive pressure of the spring 29 will require a variation in amount of resistance in order to overcome the frictional drive. As heretofore stated, this mechanism is located within the casing, and the parts are so arranged and the casing so formed as to cause a lubricating action to the members 27 and 28, this being provided by causing the gear or pinion 20 to travel within the lubricant which transfers it to gear 21 and thus reaches the members 27 and 28. By providing this lubricating action, the excessive wear usually present in devices of this type is materially reduced, thus permitting the proper compression of spring 29 to be provided, after which the casing is closed to render it inaccessible to the operator, with a surety that the general frictional relationship between the members will be substantially maintained; in this manner, frequent adjustment of pressure is not required, thereby enabling the use of a substantially dust-proof casing. By this arrangement, it will be understood that the friction developed within the clutch is sufficient to provide a direct drive from the shaft 19 to the shaft 12 under ordinary conditions, the particular amount of resistance which can be overcome without affecting this direct drive being determined by the pressure exerted by spring 29. Should, however, an increase of resistance be provided, as by an accumulation of material in advance of the charger, or a failure to open the discharging door, or a sticking of the charger during its movements into and out of the retort, the slip action provided by the clutch will enable the motor to operate without damage until the operator is able to remedy conditions.

Where the resistance is provided simply by an accumulation in advance of the charger, a reversal of the direction of rotation of the motor will permit the charger to be readily withdrawn so as to prevent material damage to the scoops. However, where the resistance is provided by a sticking action of the scoops, this reversal may be insufficient to overcome the resistance, and for the purpose of remedying this condition and permit the operator of the machine to take these steps without delay, we employ an emergency mechanism by means of which the operator is able, as soon as the condition is discovered, to bring into action a manually-operated structure connected directly to the shaft 12 and by means of which a leverage of considerable power may be placed on the shaft for the purpose of relieving the sticking condition. Since this condition is generally provided within a small portion of the length of the charger, the condition may be overcome by comparatively small movements if applied in the proper direction, and for this reason the emergency mechanism sacrifices speed of operation to the obtaining of power, the speed being obtained by the operation of the motor after the sticking condition has been overcome. This emergency mechanism will now be described. 32 designates a shaft carrying pinion 33 at its inner end, said pinion being adapted to mesh with gear face 24^b carried by the member 24, the shaft 32 having its opposite end formed as one of the members of a coupling, the complementary member being carried by the shaft 34 mounted in suitable bearings and preferably extending through a tubular portion 35. The opposite end of the shaft 34 is provided with a journal 36 operatively connected to a lever

arm 37 mounted on a shaft 38, said shaft being provided with a foot lever 39 and a suitable counter-weighted device such, for instance, as shown at 40. The shaft 34 preferably extends at an angle to the vertical and the horizontal, the degree of inclination being such as to provide for an efficient application of power by the foot lever 39, to thrust the shaft 34 into engagement with shaft 32 by an endwise movement of the shaft 34, the counter-balance 40 normally holding the shaft 34 out of such engagement. A gear 41 is splined or otherwise secured to the shaft 34, said gear moving with the shaft in a rotational direction, the shaft, however, being permitted to move axially of the gear to provide for the shifting operation referred to. The gear 41 engages a pinion 42 carried by a vertical shaft 43 to the upper end of which is secured an operating wheel 44, the parts being so arranged as to be practically inclosed and therefore practically free from the collection of dust, etc., by the coacting parts. As will be seen, the gear ratio throughout the connections is in a direction for increasing the power from the wheel 44 to the gear 24^b, and since the power exerted by the wheel 44 is applied on the threaded shaft 12, it will be readily understood that the power which may be provided manually by the operator is so multiplied in reaching the nut 13 as to cause the manual operation to be sufficient to break the sticking action.

As will be readily understood, while the particular arrangement of multiplying gearing will have the effect of multiplying the power applied to the hand wheel 44, it will also have the effect of multiplying the speed when the source of power is changed to the motor, the speed increase being such as would tend to cause manual operation of the hand wheel 44 to be dangerous. To overcome this effect, we preferably provide means for automatically disconnecting the drive from the motor to shaft 12 when the emergency mechanism is in service. This means may be in the form of mechanism for breaking the circuit for motor 14, as shown in Figs. 1 and 2, the make and break device being under the control of the foot lever 39 and acting to normally close the motor circuit at this point. When it is desired to operate the emergency mechanism, the movement of the lever 39 in a direction to engage shaft 34 with shaft 32, will automatically break this motor circuit, and retain it broken until the lever is again released. This mechanism is shown diagrammatically in the drawings at 50. As will be obvious, the motor will be inoperative as long as the emergency mechanism is shifted to provide a drive from wheel 44 to shaft 12.

By the particular arrangement shown, it will be obvious that the connections be-

tween the shafts 32 and 34 will permit rapid engagement and disengagement, the rapid engagement enabling the operator to bring the manual operation into effect as quickly as possible, while the rapid disengagement insures against injury to the operator when normal conditions are restored, and the full effect of the motor operation is placed on the shaft 12.

As will be obvious, the emergency mechanism is not adapted for permanent engagement with shaft 12, being arranged to be operatively connected to that shaft only under emergency conditions, the speed of operation being necessarily slow and hence impractical for providing the sole means of manipulating the charger to and from charging position, the time required for such action being such that the high temperatures of the retort would destroy the charger before it could be withdrawn. The mechanism acts simply as an emergency mechanism for overcoming sticking actions of the scoops, and relieving this action in order to permit the motor to rapidly withdraw the scoops, the operator retaining his foot on the foot lever 39 while manipulating the hand wheel 44. As soon as the release of the sticking condition is sensed by the operator through overcoming the resistance, the foot is withdrawn, permitting the lever to return to its inoperative position under the action of the counter-balance 40, thus again completing the circuit to the motor which then completes the operation entirely independent of the emergency mechanism.

While we have shown a preferred form of emergency mechanism for producing the desired results, it will be understood that changes and modifications therein may be required or desired to meet such conditions, and we, therefore, reserve the right to make any and all such changes or modifications as may be found necessary or desirable in so far as the same shall fall within the spirit and scope of the invention as expressed in the accompanying claims.

By the particular arrangement shown, it will be understood that the emergency mechanism practically by-passes the motor connections to the threaded shaft. Hence, there is no requirement of varying the degree of pressure placed on the friction clutch when operating the emergency mechanism.

What we claim is:—

1. The combination with a charger adapted to be entered into and providing the charging operations for a retort, and means for moving the charger to provide its normal retort entering and withdrawal movements, of normally-inactive auxiliary means permanently positioned with respect to the charger moving means and adapted to be operatively connected thereto at will for

effecting charger movements under emergency conditions within the retort, said auxiliary means being incapable of providing the normal charging operations.

5. 2. The combination with a charger adapted to be entered into and providing the charging operations for a retort, and means for moving the charger to provide its normal retort entering and withdrawal movements, of normally-inactive manually-operated auxiliary means permanently positioned with respect to the charger moving means and adapted to be operatively connected thereto at will for effecting charger movements under emergency conditions within the retort, said auxiliary means being incapable of providing the normal charging operations.

3. The combination with a charger adapted to be entered into and providing the charging operations for a retort, and means including a threaded member for moving the charger to provide its normal retort entering and withdrawal movements, of normally-inactive manually-operated means permanently positioned with respect to the charger moving means and adapted to be operatively connected to the threaded member at will for effecting charger movements under emergency conditions within the retort, said auxiliary means being incapable of providing the normal charging operations.

4. In combination, a charger adapted to be entered into and providing the charging operations for a retort, a threaded member operatively connected to the charger to provide its retort entering and withdrawal movements upon rotation of the member, a motor, a clutch device intermediate the motor and the threaded member, said motor and clutch device operating the threaded member to provide the normal charging operations of the charger, and normally-inactive manually-operated means permanently positioned with respect to the threaded member and adapted to be operatively connected direct thereto at will for effecting charger movements under emergency conditions within the retort.

5. In combination, a charger adapted to be entered into and providing the charging operations for a retort, a threaded member operatively connected to the charger to provide its retort entering and withdrawal movements upon rotation of the member, a motor, a friction clutch device intermediate the motor and the threaded member, said motor and clutch device operating the threaded member to provide the normal charging operations of the charger, and normally-inactive manually-operated means permanently positioned with respect to the threaded member and adapted to be operatively connected direct thereto at will for

effecting charger movements under emergency conditions within the retort, said device permitting action of the manually-operated means independent of the motor.

6. In combination with a charger adapted to be entered into and providing the charging operations for a retort, and means for moving the charger to provide its normal retort entering and withdrawal movements, of normally-inactive auxiliary means permanently positioned with respect to the charger moving means and adapted to be operatively connected thereto at will for effecting charger movements under emergency conditions within the retort, said latter means including a gear train decreasing in speed toward said charger moving means.

7. In combination, a charger adapted to be entered into a retort, a threaded member operatively connected to the charger to provide its retort entering and withdrawal movements upon rotation of the member, a motor, and a friction clutch intermediate the motor and the threaded member, said clutch device comprising a pair of members, secured to the threaded member, a gear member free from direct engagement with said pair of members, and having an operative connection with the motor shaft, friction members carried by the gear member, and friction members carried by said pair of members, said friction members opposing said gear member and the pair of members and being arranged in alternation.

8. In combination, a charger adapted to be entered into a retort, a threaded member operatively connected to the charger to provide its retort entering and withdrawal movements upon rotation of the member, a motor, and a friction clutch intermediate the motor and the threaded member, said clutch device comprising a pair of members secured to the threaded member, a gear member free from direct engagement with said pair of members, and having an operative connection with the motor shaft, friction members carried by the gear member, and friction members carried by said pair of members, said friction members opposing said gear member and the pair of members and being arranged in alternation, and means for applying pressure to said members in directions to provide the frictional engagement.

9. In combination, a charger adapted to be entered into a retort, a threaded member operatively connected to the charger to provide its retort entering and withdrawal movements upon rotation of the member, a motor, and a friction clutch intermediate the motor and the threaded member, said clutch device comprising a pair of members secured to the threaded member, a gear member free from direct engagement with said pair of members, and having an operative

- connection with the motor shaft, friction members carried by the gear member, and friction members carried by said pair of members, said friction members opposing said gear member and the pair of members and being arranged in alternation, and means for applying adjustably regulated pressure to said members in directions to provide the frictional engagement.
10. In combination, a charger adapted to be entered into a retort, a threaded member operatively connected to the charger to provide its retort entering and withdrawal movements upon rotation of the member, a motor, and a friction clutch intermediate the motor and the threaded member, said clutch device comprising a pair of members secured to the threaded member, a gear member free from direct engagement with said pair of members, and having an operative connection with the motor shaft, friction members carried by the gear member, and friction members carried by said pair of members, said friction members opposing said gear member and the pair of members and being arranged in alternation, and a lubricant-containing casing for said device, said gear connections acting to provide automatic lubrication to the friction members.
20. 11. In combination, a charger adapted to be entered into a retort, means for moving the charger to provide its retort entering and withdrawal movements, auxiliary means for manipulating the charger in the direction of such movements, and means for preventing concurrent operations of said charger moving means and auxiliary means.
25. 12. In combination, a charger adapted to be entered into a retort, means for moving

the charger to provide its retort entering and withdrawal movements, said means including a motor and its circuit, and auxiliary means for manipulating the charger in the direction of such movements, said auxiliary means having a make and break device in said motor circuit.

13. In combination, a charger adapted to be entered into a retort, means for moving the charger to provide its retort entering and withdrawal movements, said means including a motor and its circuit, and auxiliary means for manipulating the charger in the direction of such movements, said auxiliary means having a make and break device in said motor circuit, the movement of said auxiliary means to activity operating to break the motor circuit.

14. In combination, a charger adapted to be entered into a retort, means for moving the charger to provide its retort entering and withdrawal movements, said means including a motor and its circuit, and auxiliary means for manipulating the charger in the direction of such movements, said auxiliary means having a make and break device in said motor circuit, the movement of said auxiliary means to activity operating to break the motor circuit at said make and break interruption, said interruption remaining broken during the period of activity of the auxiliary means.

In testimony whereof, we affix our signatures in presence of two witnesses.
